DAMON R. THROOP, OF STOCKTON, CALIFORNIA

AUTOMATIC REVOLVING SCRAPER

Application filed July 15, 1929. Serial No. 378,240.

This invention relates to scrapers of the turnable bowl or Fresno type, and particularly to one of large size adapted to be drawn by a tractor.

5 The principal object of my invention is to provide a scraper of this general character so constructed that the bowl when full will be automatically moved from scraping engagement with the ground without any attention 10 on the part of the operator being necessary. At the same time should it be desired to take on a heavier load it is only necessary for the operator to pull forward on a loading lever for the necessary length of time to effect the completion of the loading—an operation which 15 on account of the effectiveness of the lever provided is very easily accomplished.

By reason of my improved automatic loading control feature it is impossible to 20 stall the tractor regardless of any attention on the part of the operator, since as soon as the proper load has been attained the scraper automatically ceases scraping and loading, thus relieving the tractor of any strains other 25 than that of the accumulated load. In connection with this point it is of course necessary that the scraper shall be first adjusted according to the dirt conditions and the pulling capacity of the particular tractor being 30 used.

The automatic control mechanism functions efficiently regardless of the different kinds and relative weight of the dirt being scraped. Dumping or spreading operations 35 are also controlled very easily merely by a light pulley on the trip lever.

The same automatic control mechanism with a few modifications may also be readily incorporated in a scraper of the wheel supported type so that the blade of the bowl may 40 be either raised just to a non-scraping position or to a position fully clear of the ground for transportation when empty.

These objects I accomplish by means of 45 such structure and relative arrangement of parts as will fully appear by a perusal of the following specification and claims.

In the drawings similar characters of reference indicate corresponding parts in the 50 several views:

Fig. 1 is a side elevation partly in section of my improved scraper in a loading position.

Fig. 2 is a similar view showing the position of the parts after a full load has been obtained and the scraper bowl has been raised to a non-scraping position. 55

Fig. 3 is a top plan view of the scraper in a loading position.

Fig. 4 is a fragmentary cross section on the line 4—4 of Fig. 1. 60

Fig. 5 is a similar view on the line 5—5 of Fig. 1.

Fig. 6 is a side elevation of a modified form of wheel mounted scraper. 65

Referring now more particularly to the characters of reference on the drawings, and particularly to Figs. 1 to 5, the numeral 1 denotes the main frame beams of the structure, which at their forward ends are disposed in parallel and spaced relation to each other and then diverge toward their rear ends to receive the bowl 2 therebetween, which bowl is pivoted substantially centrally of its length on trunnions 3. Runners 4 concentric with the trunnions project upwardly from the bowl at its sides for engagement with the ground when the bowl is in a spreading or dumping position, as is customary in devices of this character. 70 75

The tractor used in hauling the machine is not connected to the frame itself but to the forward end of a tongue 5. This tongue is slidably disposed and guided between the frames 1 at their forward ends and projects through the cross member 6 of an auxiliary frame and brace structure 6a which is provided in rigid relation with the frame intermediate its front end and the bowl. Rollers R on the frame at its front end engage the top and bottom of the tongue at spaced points and prevent the displacement of the same relative to the frame while facilitating real lengthwise movement therebetween. 80 85

Rearwardly of the member 6 the tongue has a heavy and normally slack compression spring 7 thereon which bears at one end against said member 6 and acts to resist the forward movement of the tongue relative to the frame. Such forward movement of the 90 100

tongue is limited by a stop 8 fixed on the tongue and positioned to engage a longitudinally adjustable stop 9 mounted on the frame ahead of said stop 8.

- 5 Pivoted on the frame just ahead of the bowl is a transverse shaft 10 from which outside the bowl arms 11 project rearwardly to engage the under side of circumferentially spaced stop pins 12 which project laterally 10 from the bowl concentric with the trunnions to normally prevent rotation of the bowl. A normally vertical arm 13 projects upwardly from the shaft centrally between its ends and is pivotally connected to one end of a forwardly extending catch bar 14. This bar has a notch 15 in its under face near its forward end to normally receive a pin 16 fixed on a vertical link unit 17 which is pivoted toward its lower end to the auxiliary frame structure 20 6a just below the tongue. The pivot pin 18 of this spring unit preferably has a roller 18a thereon on which the lower edge of the tongue rides. A tension spring 19 between the bar 14 and the frame holds said bar engaged with 25 the pin, and another tension spring 20 connects the arm 13 and the link 17 to cause the catch bar to return to its normal longitudinal position after it has been released. A trip lever 21 is pivoted at one end on the link preferably in common with the pin 16 and projects thence rearwardly and then upwardly, being connected at its upper end with a forwardly extending pull cord 22. At its lowermost point the trip lever has a roller 23 passing under the bar 14. Upon pulling the cord therefore the roller will be raised against the bar and the latter will be disengaged from the pin. This allows the weight and forward rotating tendency of the bowl to push the 30 arms 11 down so that the adjacent pins 12 will clear the arms and the bowl will assume a spreading or dumping position. As usual one set of stops 12 controls the scraping position of the blade of the bowl, while the other controls the spreading position.
- 40 Between the pivot and catch pins 18 and 15 the link 17 has another pin 24 placeable in a number of vertically spaced holes 25. This pin rides in a longitudinally slotted member 26 projecting rearwardly from and pivoted on a bracket 27 secured to and projecting upwardly from the tongue 5. A hand loading lever 28 is pivoted adjacent its lower end on the tongue ahead of the bracket as at P and is connected to the lower end of the link 17 by links 29 which toward their forward ends have longitudinal slots 29a through which a cross pin 30 on the lever projects a short distance above its pivot.
- 45 In operation when the bowl is in a loading position the tongue is in its rearmost position relative to the frame 1, the pin 24 is at the rear end of the slot in the member 26; the pin 30 is toward the rear end of the slot 29a, while the stops 8 and 9 are separated from each other.

This position of the parts will be maintained until a load of a certain amount has been scraped into the bowl. The resistance of this load to the forward movement of the machine will then cause the pull of the tractor to overcome the resistance of the spring 7 and the latter will be compressed until the tongue has moved ahead relative to the frame so that the stops 8 and 9 abut against each other, of course preventing further forward movement of the tongue. With this movement of the tongue however the member 26 (which is connected to the tongue) is moved forwardly. This causes the upper end of the link 17 to be moved forwardly also, imparting a corresponding movement to the arm 13 and causing the arms 11 to be raised.

The raising of said arms of course through the medium of the stop pins 12 with which they are engaged, causes the bowl to turn rearwardly on its trunnions until the blade is just level with the ground or in a non-scraping position. This position will then be retained while the scraper is drawn along the ground as long as the load remains in the bowl. Should the operator however decide that he desires to take a still heavier load, all he has to do is to pull forwardly on the rope 31 which is attached to the upper end of the lever 28. Since with the forward turning 95 of the upper portion of the link 17 as above described the lower end thereof moves rearwardly, the pin 30 in the lever 28 will now be at the front end of the slot 29a. The forward pull on the lever 28 therefore acts to 100 pull the links 29 forwardly, restoring the link 17 to its original position; or in other words moving its upper end rearwardly and causing the arm 13 to be moved rearwardly and the arms 11 to be lowered. Such movement of the link 17 can only be had with the rearward movement of the tongue relative to the frame, so that not only the link but all the parts of the structure are restored to their original positions. The total length 105 and effectiveness of the lever relative to the point of connection of the pin 30 therewith is such as to enable this to be accomplished without excessive effort. The bowl being always in contact with the ground will then 110 of course reassume its scraping position and will remain in that position until the pull on the lever 29 is released. When the lever is thus released the bowl will at once again raise to its non-scraping position owing to 115 the functioning of the tongue and the control mechanism, as previously described.

When it is desired to cause the contents of the bowl to be spread it is only necessary for the operator to pull on the cord 22, when the arm 14 will be released from connection with the link 17 irrespective of the position of the latter; and the bowl will then be free to rotate to a spreading position as previously described. If it is desired to dump 120

rather than spread the load it is only necessary to retain a pull on the cord 22 until both sets of stops 12 have moved past the arms 11.

The provision of the plurality of holes 25 in the link unit 17 enables the point of connection of the member 26 with said link, relative to the pivot 18, to be altered. This obviously alters the leverage exerted by the member 26 on the link and enables the necessary adjustments to be made according to whether the dirt being scraped is of a light or heavy nature.

In the type of device shown in Fig. 6 in which the frame 1a is supported by wheels 32 which are preferably journaled on the trunnions 3a of the bowl 2a, the automatic control mechanism is substantially the same as above described. The weight of the bowl 20 however is distributed relative to the trunnions so that it tends to tip down and forwardly of itself to a digging position, since it is normally not engaged with the ground. The bowl stop pins 12a are arranged as pairs 25 and instead of the plain arms 11 of the other type, segmental gear members 11a to engage the pairs of pins are provided. Also an additional tension spring 33 is connected to and extends rearwardly from the link unit 17a. Otherwise the construction and arrangement of the parts is the same. In the operation of this type the forward movement of the tongue 5a relative to the frame causes the bowl as before to tilt rearwardly 30 until the blade just rides on the ground.

The weight of the load is sufficient to prevent the spring 33 functioning to further raise the bowl as long as the load is held therein. After the contents of the bowl have been spread or dumped and the bowl is empty however said spring 33 acts to pull the upper end of the link 17a rearwardly, thus acting on the trip bar 14a and the arm 13a to raise the members 12a and likewise turn the bowl 45 on its trunnions so that its blade will be well clear of the ground, as indicated in dotted lines. A pull on the loading lever 28a then reverses the position of the link 17a and causes the bowl to be lowered to a scraping position 50 just as described in connection with the first type. It is however necessary to retain a pull on this lever until a certain amount of dirt has been scraped into the bowl sufficient to overcome the tendency of the spring 33 to raise 55 the bowl to a transporting position.

The above structure represents a considerable improvement in the operation and control of wheel mounted scrapers, in which the bowl can usually be moved only to a ground 60 clearing position. This usually causes a considerable portion of the load to be lost before it has been transported to the place where it is to be dumped on account of the fact that the blade is not engaged with the ground 65 and any dirt which spills out from the front

cannot be salvaged. By retaining the blade against the ground however just as in the drag type, this objectionable feature is overcome and the wheel mounted type has all the advantages of the drag type with the additional benefits had by reason of the wheels, which facilitate transportation of the scraper as will be obvious. 70

From the foregoing description it will be readily seen that I have produced such a device as substantially fulfills the objects of the invention as set forth herein. 75

While this specification sets forth in detail the present and preferred construction of the device, still in practice such deviations from such detail may be resorted to as do not form a departure from the spirit of the invention, as defined by the appended claims. 80

Having thus described my invention what I claim as new and useful and desire to secure 85 by Letters Patent is:

1. A scraper including a rotatable bowl, a frame supporting the bowl in a manner to cause the same, when the frame is drawn forwardly, to assume a scraping position, a draft tongue forwardly movable relative to the frame, a spring normally resisting such movement of the tongue, a stop projecting from the bowl ahead of the axis of rotation thereof, a transverse shaft on the frame ahead of the bowl, an arm projecting rearwardly from said shaft and under the stop, a vertical arm upstanding from the shaft, a vertical link pivoted on and projecting upwardly from the frame ahead of the shaft, 100 a connecting bar between the vertical arm and link above the pivot of the latter, and a member mounted at its forward end in connection with the tongue and connected at its rear end with said link above the pivot 105 thereof.

2. A structure as in claim 1, in which the point of connection of said member with the link is adjustable relative to its distance from the link-pivot, whereby to alter the leverage 110 effect on the link and the arcuate distance through which the same will swing with a certain forward movement of the tongue relative to the frame.

3. A structure as in claim 1, in which the bar is disengageably connected to the link, and trip means is mounted on the link to effect such disengagement at will. 115

4. A structure as in claim 1, with a hand lever pivoted on the tongue ahead of the link, 120 a pin projecting from the lever above its pivot, and a substantially horizontal link extending from the vertical link below its pivot to the lever and having a longitudinal slot through which said pin projects; the pin being at the front end of the slot when the bowl has been turned to a non-scraping position by the relative forward movement of the tongue. 125

5. A structure as in claim 1, with a hand 130

lever pivoted on the tongue and operatively connected to the link to move the portion of the same above its pivot rearwardly with a forward pull on the lever.

5 6. A structure as in claim 1 with a hand lever pivoted on the tongue, and connections between the lever and link to enable the latter to be pulled rearwardly and arranged to cause said lever to remain undisturbed until
10 the bowl has been turned to a non-scraping position.

7. A scraper including a rotatable bowl, a frame supporting the bowl in a manner to cause the same, when the frame is drawn forwardly, to assume a scraping position; a draft tongue forwardly movable relative to the frame, a spring normally resisting such movement of the tongue, connections between the tongue and bowl for turning the latter to a non-scraping position when the resistance of the spring is overcome and the tongue moves forwardly relative to the frame, and means including a forwardly moving lever for restoring the bowl to a scraping position against a pull on the tongue.

8. A scraper including a rotatable bowl, a frame supporting the bowl in a manner to cause the same, when the frame is drawn forwardly, to assume a scraping position; a draft tongue forwardly movable relative to the frame, a spring normally resisting such movement of the tongue, connections between the tongue and bowl for turning the latter to a non-scraping position when the resistance of the spring is overcome and the tongue moves forwardly relative to the frame, and a hand lever separate from but operatively connected to said connections for returning
35 the bowl to a scraping position and arranged to cause said lever to remain stationary relative to the tongue while the tongue is moving forwardly.

9. A scraper including a rotatable bowl, a frame supporting the bowl in a manner to cause the same, when the frame is drawn forwardly, to assume a scraping position; a draft tongue forwardly movable relative to the frame, a spring normally resisting such movement of the tongue, connections between the tongue and bowl for turning the latter to a non-scraping position when the resistance of the spring is overcome and the tongue moves forwardly relative to the frame, said connections including a vertical link pivoted on the frame and arranged to move forwardly at its upper end to effect such turning of the bowl; and a hand lever separate from the link and connected thereto
50 for moving the upper end of the link rearwardly with a forward pull on the lever.

In testimony whereof I affix my signature.
DAMON R. THROOP.
